SAFE PROTECTION

Charles R. Davis, Rochester, N. Y.

Application January 19, 1942, Serial No. 427,268

5 Claims. (Cl. 109—44)

This invention relates to burglar resisting safes and is in the nature of a continuation in part of my copending application Ser. No. 111,670 filed November 19, 1936, now Patent No. 2,270,274, issued January 20, 1942.

An object of this invention is to provide improved means for protecting a safe or strong box, and particularly the door and locking mechanism thereof, against tampering of a kind which might enable the box or safe to be opened by thieves or burglars, with which the protective device will be rendered effective automatically when the door and locking mechanism of the box or safe are tampered with or mutilated in an effort to open the door except by the usual manner of operating the locking mechanism, which is particularly suitable for use with combination locks, with which the protective means for the box will be ineffective when the door is unlocked, even though closed, but which will be rendered effective automatically by the act of locking of the door, and which will be relatively simple, effective, practical and inexpensive.

Another object of the invention is to provide improved, simple and efficient means for protecting the door of a safe or strong box when the door is locked, which is automatically rendered ineffective when the door is unlocked, and which will be effective against mutilation of the locking mechanism, against drilling, against any attempt to disable the lock by pulling the spindle from the combination lock by means of a puller or punching the spindle inwardly.

Other objects and advantages will be apparent from the following description of two embodiments of the invention, and novel features of the invention will be pointed out hereinafter in connection with the appended claims.

In the accompanying drawings:

Fig. 1 is an inside face elevation of the door of a safe or strong box, constructed in accordance with this invention, but with the removable plate on the inner face removed, a portion of the door casing broken away, and a portion of the adjacent wall of the strong box, against which the door abuts, shown in section, which corresponds to a section approximately along the line 1—1 of Fig. 2;

Fig. 2 is a sectional plan of the same, with the section taken approximately along the line 2—2 of Fig. 1;

Fig. 3 is a diagram illustrating the electrical circuits of the protective system;

Fig. 4 is a sectional elevation of a portion of the locking mechanism and circuit controlling 55

means, modified slightly from that shown in Figs. 1 to 3, and with the circuit shown diagrammatically;

Fig. 5 is a sectional elevation through a portion of the safe shown in Figs. 1 to 3, immediately behind the dial plate, and showing the manner of mounting the dial plate;

Fig. 6 is a sectional elevation through the combination lock mechanism of the door;

Fig. 7 is a sectional plan of details used for fastening the dial plate in place;

Fig. 8 is a sectional plan of a mounting for a conducting member and associated parts, and forming part of the embodiment of Figs. 1 to 3 and 5 to 7.

In the embodiment of the invention illustrated in Figs. 1 to 3, and 5 to 8, the safe or strong box 1 is of the type disclosed in my prior copending application Ser. No. 111,670 filed November 19, 1936, now Patent No. 2,270,274, issued January 20, 1942.

This safe or strong box is provided with a displaceable door 2 which is hinged to the opening of the strong box or safe in any suitable manner, such as by hinges 3. The safe or box 1 is provided with a hardened outer steel jacket or plate 4, and against the inner face of this plate 4 is disposed a relatively thin layer of insulating material 5, such as a thin layer of insulating varnish, or a layer of "Empire cloth" which is an impregnated textile fabric commonly used for insulating purposes. Against the insulating layer 5 is disposed a plate or layer 6 of conducting material such as copper wire screening. This screen layer 6 and the insulating layer 5 abut each other face to face and flat against the inner face of the steel jacket 4. Against the screen 6 I dispose another layer 7 of suitable insulating material. A filler 8 of heat insulating material such as plaster of Paris or other suitable heat insulating material is disposed to substantially fill the space between the insulating layer 1 and the inner wall 9 of the safe which defines the storage chamber.

Similarly, the door 2 is provided with an outer steel plate or layer 10, against the inner face of which is disposed a thin insulating layer 11 similar to the layer 5, and a conducting layer 12 is disposed flat against the insulating layer 10. The layer 12 may also be of copper wire screening similar to the layer 6, but it will be understood that metal foil or other electrically conducting material may be employed as the inner conducting layers 6 and 12. The layer 12 is also covered by an insulating layer 13 and that in turn is covered

by a metal plate 14. The space between the plate 14 and the rear wall 15 of the door may be filled with a suitable filler 16, similar to the filler 8, except that space is provided for the locking and protective mechanism carried in the door. The inner wall or face 15 of the door may have a removable plate 17 to enable access to be had to the locking mechanism and electrical connections. This plate 17 was removed in Fig. 1, in order to show the interior of the door chamber.

The door is provided with a lock spindle 18 which extends through the plates or layers 10, 12 and 14 and insulating layers 11 and 13, and is insulated from the plates or layers, such as by mounting the spindle 18 in a fiber bushing which extends through all of these layers. The spindle 18 carries an operating handle 19 on the outer end thereof. The inner end of the spindle 18 is provided with a crank disk 20 carrying, eccentric to the axis of the spindle, a crank pin 21 which engages in an elongated slot 22 in a cross head or yoke 23 which carries locking bolts 24 at opposite ends of the arms thereof. These locking bolts 24 are disposed to extend through aligned openings 25 in the abutting plates of the door and door opening of the strong box in order to lock the door. By moving the bolts 24 through the aligned openings 25, the door may be locked in closed position, and by retracting the bolts 24 entirely into the door, the door will be released so that it can swing into open position. The bolts are projected into locking position or withdrawn merely by rocking the handle 19 and through it the spindle 18. During this rocking of the spindle 18, the pin 21 acts as a crank in the slot 22 and causes reciprocation of the yoke 23 and locking bolts 24. The yoke or cross head 23 is also provided with an elongated slot 26, at right angles to the slot 22, which receives a guide pin 27 projecting from the inner plate 14 and the slot 26, by the engagement of its opposite ends 22 with pin 27, limits the movement of the locking bolts 24, although the throw of the crank pin 21 would also serve the purpose.

Also mounted on the inner face of the plate 14 of the door is a suitable combination lock 28 having a plurality of tumblers which, when properly set, control the yoke 23 and locking bolts 24. Such combination locks are purchased in the open market and the details of the same, per se, are not a part of this invention except as specifically pointed out herein. The tumblers in such a lock are mounted on a metal spindle 29, see Fig. 6, which is rotatably mounted in bearings 30 and 31 disposed in a bushing 32 of insulating material such as of fiber. The bushing extends through the metal plates 10, 12 and 14 and insulating layers 11 and 13. A fiber nut 33 is threaded upon the outer end of bushing 32 and serves to clamp a metal dial plate 34 against the outer face or plate 10 of the door 2, there being an insulating layer 35 disposed between the dial plate 34 and the plate 10 which is of steel or other electrically conducting material. A button 36 fixed upon the outer end of the spindle 29, serves as a medium by which the spindle 29 may be rotated to set the tumblers to release the locking mechanism, or to lock the bolt mechanism, the tumblers being designated generally at 37 in Fig. 6, and the spindle 29 extends on through the same.

The bearing 31 may have an annular groove in its periphery into which the adjacent end of the fiber bushing 32 may be forced, or the bearing 31 may be threaded into the interior of the passage of the bushing 32, and this bearing 31 has a shoul-

der portion abutting against the end of the bushing 32, which shoulder portion receives upon it one wall of a casing 38 which is secured against plate 14 by a nut 39 screwed upon the bearing 31. The spindle 29 projects through an opening 40 in the rear face of the casing 38.

A U-shaped metal bracket 41 straddles the casing 38 with the arms of the U extending toward the front of the door and spaced from the casing 10 38 by insulating strips 42 and 43. This bridge 41 is secured to the upper and lower sides of the casing 38 in any suitable manner, such as by bolts 44 which are insulated from the casing 38, but electrically connected to the bridge 41.

15 The spindle 29 extends through an opening 45 in the cross part of the bridge 41 and out of contact with bridge 41, and on opposite sides of this opening 45, the spindle carries metal pins 46 which are normally slightly spaced from the 20 bridge 41, so that if the spindle 29 of the combination lock is given an endwise movement in either direction, such as by pulling outwardly on the spindle with a wheel puller or similar device, or by driving the spindle inwardly, one of the pins 25 46 will contact with the bridge 41 and thus electrically connect the bridge 41 with the spindle 29. The spindle 29 carries a metallic disc or dial 47 which is electrically grounded or connected to the spindle 29, and overlies a substantial area of 30 the dial plate 34, and the edge of the dial 47 terminates in close proximity to but is slightly spaced from, the dial plate 34, with no insulation between them. Operated by the tumbler mechanism in the usual manner is a link 48, Figs. 1 and 35 2, which, when the tumblers are properly set and turned by proper manipulation of the button 36, will be moved generally endwise.

This link 48 is pivotally connected to a locking lug or member 49 which is slidably mounted in 40 the casing 38, so as to extend beyond the casing 38 to some extent and be movable into the path of an upstanding flange 50 on the yoke 23. Thus when the locking lug or member 49 is moved in an outward direction into the position shown in 45 full lines in Fig. 1, it abuts against the flange 50 and prevents retraction of the yoke 23. When the lug 49 is moved inwardly it moves away from the flange 50 and releases the yoke 23 for movement in a direction to withdraw the bolts 24 from locking 50 position.

The locking lug 49 carries an angular member 51 Fig. 1, and upon the free end of the member 51 I support a generally U-shaped metallic member 52. The member 52, see Fig. 8, is insulated 55 from the member 51 by a washer 53 of insulating material, and a bushing 54 of insulating material passes through an aperture 55 in the member 52 and terminates in a flange 56 at the face of member 51 opposite the member 52. A bolt or 60 rod 57 of electrically conducting material such as metal, passes through the bushing 54 and the end of the member 52 which abuts against the end of member 51. Nuts 58 and 59 are threaded upon the rod 57 so as to abut respectively against the flange 56 and against an arm of member 52, and clamp the member 52 to the member 51. This same clamping means serves to electrically connect the member 52 to the rod 57.

The rod 57 is slidably received in a long tube 65 60 of insulating material which is threaded or tightly forced into an opening 61 in the metallic side wall 62 of the door. The adjacent wall 63 of the door jamb against which the door abuts is provided with an opening 64 which is aligned 70 with the opening 61 when the door is closed and

the rod 57 is movable or projectable through the opening 64 when the locking lug 49 is moved into locking position, as shown by full lines in Figs. 1 and 2. The rod 57 is spaced slightly from the peripheral wall of the opening 64 so that it is normally out of contact therewith when the door is locked.

The dial plate 34 is secured to the front face of the door not only by the fiber nut 33, but also by other mechanism shown in Figs. 5 and 7, and which will now be described. The dial plate 34 and front wall 10 are provided with a plurality of aligned openings through which pass bushings 65 of electrically insulating material, each of which at its outer end has a flange 66 which overlies the dial plate 34 sufficiently to confine the dial against the plate 10 of the door. A bolt 67 passes through each bushing 65 and at its inner end carries nuts 68. A washer 69 of insulating material is disposed between the nuts 68 and the inner face of the plate 10, so that the bolt 67 is fully insulated electrically from both the plate 10 of the door and the dial plate 34. Three of such bolts 67 are illustrated, and in addition, a contact stud to be described presently provided for making an electrical connection to the dial plate.

Referring now to Fig. 2, the plates 10, 12 and 14 of the door and the insulating layers 11 and 13 are provided with aligned openings through which passes a bushing 70 of insulating material. A bolt 71 passes through the dial plate 34, the insulating layer 35, the bushing 70, and at its inner end carries a nut 72. A washer 73 of insulating material is disposed between the nut 72 and the inner plate 14, and the end of a wire or conductor 99 is clamped between the nut 72 and the washer 73 so as to have an electrical connection to the bolt 71. The head of the bolt 71 overhangs and engages the dial plate 34, so as to form an electrical contact therewith, and this places the dial plate in electrical contact with the wire 99. The bolts 67 which clamp the dial plate to the front plate 10 of the door and the bolt 71 are all disposed beneath and are protected by the dial 47.

The portion of the wall of the strong box along the door opening and against which the free edge of the door abuts when the door is closed, is provided with an interior chamber 75 into which the locking bolts 24 and rod 57 project when the door is locked. Disposed in this chamber 75 is a normally open switch formed with spring contacts 76 and 77, and these contacts at their free ends are normally spaced apart slightly and disposed closely adjacent to the opening 64 through which the rod 57 may be projected, so that when the rod 57 is projected through the opening 64 into the chamber 75, its end will engage with the contact 76, make an electrical connection therewith, and also force the latter into engagement with the other switch element 77, as shown in Fig. 1.

The electrical circuits will next be described. Referring now particularly to Fig. 3, the strong box or safe is shown as supported on a cabinet 78, as described in my prior application above identified, and in this base 78 is disposed a suitable protective device which may be an alarm 79, or a gas releasing device as described in my prior application, or any other suitable means for protecting the safe. For simplicity, it is shown merely as an alarm, but it will be understood that this is not to be limiting, and that any suitable protective device may be employed. This

device 79 is supplied with operating current from a suitable, dependable source, such as a battery 80, one terminal of which is connected by a wire 81 to the protective device 79, the other side of the protective device being connected by a wire 82 to a normally retracted switch element 83 of a relay 84.

The switch element 83 is movable by the relay into engagement with a contact 85 when the relay 84 is energized and this contact 85 is connected by a wire 86 to the other side of the battery 80. The relay 84 is connected at one side by a wire 87 to one side of a battery 88, which like the battery 80, may be a storage battery or a dry battery. The other side of the relay 84 is connected by a wire 89 to the switch element 76 within the chamber 75 of the strong box, and the other switch element 77 within the chamber 75 of the strong box is connected by a wire 90 to the inner plate or copper screen 6 of the strong box. The other side of the battery 88 is connected by a wire 91 to the outer wall 4 of the strong box. A second, normally retracted, switch member 92 is also operated by the relay 84 into closed position, when the relay is energized, where it engages a contact 93. The switch member 92 is connected by a wire 94 to the wire 91, and the contact 93 is connected by a wire 95 to the wire 89. When the relay 84 is energized, it moves both switch members 92 and 83 into circuit closing position, and switch member 92 then completes a shunt circuit, sometimes known as a holding circuit or stick circuit, through the battery and relay 84 to hold the relay closed, even though the original circuit through the relay 84 is later broken. The movement of the switch member 83 by relay 84 renders the protective device effective, and since the relay locks itself in closed circuit condition through the switch member 92, this will cause the protective device to remain effective, even though the original circuit through relay 84 has been opened.

The rod 57, as explained above, is electrically connected to the member 52 and this member carries a clamping or terminal post or bolt 96, Fig. 1, to which a number of wires may be connected. One wire 97 electrically connects the terminal bolt 96 to the bolt 44 on the bridge member 41, another wire 98 electrically connects the bolt 96 to the copper mesh screen or conducting layer 12 of the door and still another wire 99 connects the clamping bolt 96 to the dial plate 34. The dial 47 is grounded through the spindle 29 to the outer plate 10 of the door and the latter to the outer plate 4 of the strong box through the hinges 3, and this grounding is indicated diagrammatically in Fig. 3 by the wires 100.

With the connections as thus explained, if the safe is unlocked, the rod 57 will be withdrawn from the opening 64, the locking bolts 24 will be withdrawn into the door, and the door is then free to open or close. When the rod 57 is withdrawn in this manner, it is out of contact with the switch contact 76 in the chamber 75, and the two contacts 76 and 77 are then out of contact with one another because these contacts 76 and 77 form a normally open switch. Current from the battery 88 is unable to flow because the circuit is opened at the switch contact 76. Therefore, any interference with the safe while the locking mechanism is unlocked will not energize the relay 84 or render effective the protective device 79. Even though the door is closed, the operation of the locking bolts 24 into locking position by turning of the handle 19 will not render

the device effective until the combination lock is turned into locking condition in which lug 49 prevents withdrawal of the locking bolts 24.

If, after the door has been closed and the locking bolts 24 projected into locking position, the combination lock is set to locking condition, the parts will then be in the relative positions shown in full lines in Figs. 1 and 2. With the safe fully locked, one terminal of the battery 88 will be connected by wire 87 to the relay 84 and the latter by wire 89 to the switch contact 76. The switch contact 76 is then connected by rod 57 and wires 97, 98 and 99 and the inner layer 14 of the door to the dial plate 34, and to the bridge 41. The switch element 76 is also connected to the switch element 77 which is connected to the inner layer 6 of the strong box, but until a ground or connection is established to the outer plate 4 of the strong box, or to the outer plate 10 of the door which is electrically connected by the hinges 3 to the outer plate 4 of the box, no current can flow through wire 91 back to the battery 88. The relay 84 is thus deenergized. If a burglar attempts to drill the wall of the safe, the drill in passing through the outer plate 4 and thin insulating layer 5 will engage the conducting plate or screen 6 and thus electrically connect plates 4 and 6. This completes a circuit between the switch contact 77, wire 90, screen 6, the drill, outer plate 4 and wire 91 back to the battery 88. This would deenergize the relay 84 and start an operation of the protective device 79. This operation of device 79 will continue even though the burglar may immediately remove his drill, because when relay 84 is energized, it locks itself in closed circuit position by the shunt circuit in switch member 92.

If the burglar drills the front door, so as to get at the locking mechanism, the drill in passing through the front plate 10 and insulating layer 11 will engage the screen or conducting layer 12 which is electrically connected by wire 98, the supporting member 52, and rod 57 to the contact 76. Current will then flow from the battery 88 through the relay 84, wire 89, switch element 75, rod 57, wire 98, screen 12, outer plate 10, hinges 3, outer plate 4 and wire 91 back to the battery 88. This also would set off the alarm or protective device 79, and the latter would continue active, even though the drill is immediately removed to break the initial circuit between the screen 12 and the plate 10. If instead of these drilling operations, the outer plate 10 of the door or the outer plate 4 of the box is heated by an acetylene torch to burn a hole in either plate, the bulging of the plate and heat will destroy the thin layer of insulation or render it conductive and thus complete a circuit either between the plate 4 and layer 6 or between the plate 10 and layer 12, as disclosed and claimed in my prior copending application Ser. No. 342,027, filed June 24, 1940.

If instead of any of these operations, a burglar attempted to force or jimmy the door by inserting a tool between the door and the door opening of the strong box, the forcing of the door would carry the rod 57 into contact with the peripheral wall of the opening 64 and thus electrically connect rod 57 to the wall 63, which in turn is electrically connected to the outer wall 4. This completes an electrical circuit to the relay 84 and starts an operation of the protective device. If the burglar attempts to insert a chisel or tool beneath the dial 41, it forms a connection between the dial 41 and dial ring 34

and thus completes a circuit through the relay 84. If an insulated tool is inserted between the dial 41 and dial plate 34, the resulting mutilation of the dial 41 will, because dial 41 is disposed so closely to the dial plate 34, cause a contact to be made between the dial and dial plate and complete the circuit to the relay.

If, instead of any of these operations, the burglar attempts to drive the spindle 29 of the combination lock inwardly, it will carry one of the pins 46 into engagement with the bridge 41 and thus connect the bridge 41 to the spindle and close a circuit through the relay 84. If instead of driving the spindle 29 inwardly, the burglar attempts to pull the spindle 29 outwardly, such as by a wheel puller, it will carry the other of the pins 46 into contact with the bridge 41 and complete the circuit through the relay 84. Thus any attempt to mutilate the safe, the door, or the locking mechanism, or to force the door by jimmeying will close a circuit through relay 84 and start the protective device 79 in operation, and the latter will then continue in operation even though the original circuit through the relay which was closed by the burglar is again opened.

Referring now to the embodiment shown in Fig. 4, the apparatus is substantially the same as shown in Figs. 1 to 3, and 5 to 8, except that the rod 57 which corresponds to the rod 57 of the other embodiment, instead of operating a normally open switch into closed position when projected through the opening 64, will engage in a knife contact 101 which is secured to the inner plate or layer 6 of the safe, and a second plunger 102 is provided on a member 52a corresponding to the member 52 of the first embodiment. This plunger 102 moves through a tube 102a aligned with an opening in the casing into the chamber 75, and engages and closes a normally open switch having contacts 76a and 77a, which correspond generally to the contacts 76 and 77 of the first embodiment.

The plunger 102 is electrically inert. The relay 84 is thus connected to the contact 77a and to the inner conducting layer 6 by wires 103 and 104 respectively, and the battery 88 is connected at one side by wire 105 to the switch contact 76a and at its other side by wire 106 to the plate 4 which is the outer plate of the safe. The relay switch element 92 establishes a circuit between wires 107 and 108, which are connected respectively to the wires 106 and 104. The relay switch member 83 and the circuit controlled thereby are the same as in Fig. 3 and have the same reference numerals. The circuit through the main battery 88 and relay 84 may be established by any of the actions of a burglar as described for the first embodiment, and will not again be described here.

It will be understood that various changes in the connections, details, materials, and arrangements of parts which have been herein described and illustrated to explain the nature of the invention, may be made by those skilled in the art within the principle and scope of the invention as expressed in the appended claims.

I claim:

1. In a burglar resisting safe having an electrically actuated protective device associated therewith, a source of electrical current supply, a circuit connecting the latter with the protective device, and a displaceable door to said safe, the improvement which comprises a combination lock on the door including a dial and dial spindle connected to one side of said circuit and insulated from the opposite side thereof, and an inner con-

tact element in the lock on the other side of said circuit arranged to be engaged by the spindle and to close the circuit upon endwise movement of the spindle as when punched through the lock.

2. In a burglar resisting safe of the type having an electrically actuated protective device associated therewith, a source of electrical current supply, a circuit connecting the latter with the protective device, and a displaceable door to said safe, the improvement which comprises a combination lock on the door including a dial and dial spindle connected to one side of said circuit and insulated from the opposite side thereof, an inner contact element in the lock on the other side of said circuit, and two electrical contact means on the spindle arranged to engage the contact element and close the circuit when the spindle is punched or pulled longitudinally in either direction.

3. In a burglar resisting safe of the type having a displaceable door, an electrically actuated protective device associated therewith, and a source of electrical current, the improvement which comprises a combination controlled lock for said door including a spindle, a dial mounted on said spindle, a dial plate secured against the outer face of said door and beneath said dial and insulated from said spindle and dial, and circuit connections to said dial plate and said spindle, whereby when said connections are included in a circuit connecting said source, said protective device and said dial and dial plate, with said dial and dial plate in series in said circuit, an attempt to muti-

late the combination lock which will bring said dial and dial plate into contact and complete a circuit through said protective device.

4. In a burglar resisting safe having a displaceable door, an electrically actuated protective device associated therewith, a source of electrical current, and a locking bolt carried by the door and operable into locking engagement with the safe when the door is closed, the improvement which comprises a combination lock controlling said bolt and having tumblers and a tumbler-setting spindle extending outwardly through the outer face of the door and rotatably to set said tumblers to lock and unlock said bolt, and normally open contact means operable into circuit closing condition upon movement of the spindle in each endwise direction, whereby when a circuit includes in series said contact means, said source, and said protective device, any attempt to pull the spindle or drive it inwardly will complete the circuit to said protective device.

5. In a burglar resisting safe of the type having a displaceable door, the improvement therefor which comprises a combination lock for releasably securing said door in closed position and having a dial and cooperating ring electrically insulated from each other, and circuit wires leading to said dial and ring whereby when said wires are included in series in a control circuit for an alarm device, mutilation of said lock will initiate an operation of said alarm device.

CHARLES R. DAVIS.
